 Filed Aug. 4, 1966, Ser. No. 570,268
 1 Claim. (Cl. 81—90)

ABSTRACT OF THE DISCLOSURE

A one-piece wrench adapted for operative engagement with various sizes of flanged collars or pipe unions for screw-threading the same into secure engagement with, or removal from a pipe.

This invention relates to improvements in wrenches well adapted, though not restrictively, for applying flanged collars or couplings to the screw-threaded ends of pipes.

One of the principal objects of the invention is to provide a wrench of this character which is of durable, inexpensive, simplified construction, capable of securely gripping and expeditiously screw-threading a pipe flange into secure engagement with the threaded end of a pipe or readily removing the same by merely reversing the wrench.

The foregoing and other objects and advantages which will become subsequently apparent reside in the details of construction and operation as more fully hereinafter described and claimed, reference being had to the accompanying drawing forming a part hereof and in which:

FIGURE 1 is a plan view of a wrench made in accordance with my invention and shown in operative driving engagement with the flange of one size of pipe coupling.

FIGURE 2 is a view similar to FIGURE 1 showing the wrench similarly engaged with the flange of a larger size coupling.

FIGURE 3 is a side elevational view of FIGURE 1, and

FIGURE 4 is a view similar to FIGURE 3 showing the wrench rotated through 180 degrees about its longitudinal axis into unscrewing engagement with the pipe flange.

With continuing reference to the drawing wherein like reference characters designate like parts, the main body of the wrench comprises a plate 1 provided with a pin 2 extending through the forward end thereof and secured thereto in any suitable manner.

The opposite end of plate 1 extends beyond the peripheral edge of any size or diameter of coupling flanges being dealt with.

The opposite end of the plate 1 is bifurcated as at 3 and welded therein as at 4 is a handle component in the form of a sleeve or socket 5 which may be either smooth-bored or internally threaded for removable securement to a handle 6 which may be of any desired length to meet leverage requirements.

Also permanently secured to opposite sides of plate 1, by welding or the like as at 7, in diagonal relation to the plate are matched angle sections 8 and 9.

The couplings herein shown and described are exemplary of any such conventional pipe unions ranging from the approximate small size shown in FIGURE 1 to the relatively large size shown fragmentarily in FIGURE 2.

The coupling comprises an internally threaded collar 12 for conventional securement to the threaded end of a pipe 13 by means of an integral flange 14 having diametrically opposed apertures 15 therein.

In applying the coupling to the threaded end of a pipe 13 and as best illustrated in FIGURE 1, the plate-like main body member 1 of the wrench is placed flat-

2

wise upon the coupling flange 14 with the bottom portion of the pin 2 extending through one of the apertures 15 in the flange. Then moving the handle 6 and hence the plate 1 in a clockwise direction will bring the inside surface of the flange of angle section 9 (FIG. 3) into tangential engagement, as at 18 (FIG. 1), with the peripheral edge of the flange 14.

The flange-engaging end of the plate 1 is recessed as at 20 so there will not be any interference with the pipe or flanges being dealt with.

From the foregoing it will be obvious that when the pin 2 is engaged with either pipe flange 14-14A and the inside surface of the flange of the angle section 9 (FIG. 3) is in abutting engagement with the periphery of the flange the coupling may be quickly screwed upon the threaded end of its respective pipe by clockwise rotation of the wrench, and that by reversing the position of the wrench by rotation about its longitudinal axis to re-engage the pin 2 with another of the flange apertures with the opposite or outside surface of the flange of angle section 8 in engagement with the periphery of the flange, as in FIGURE 4, the coupling may be quickly and conveniently unscrewed from the pipe section by counterclockwise rotation. Thus it will be seen that I have provided a wrench of greatly simplified construction involving no moving parts, capable of quick application to a coupling flange for rotating the same in either of two directions in a horizontal plane. The flange-engaging pin 2 and the inside or outside surfaces of the angle sections 8-9 cooperate in automatically establishing a fulcrum point upon contact of those surfaces with the periphery of the flange for a lever of the first order and in maintaining the main body plate member 1 in flat facial contact with the coupling flange during either clockwise or counterclockwise operational rotation of the wrench.

As above stated the recessed edge 20 of the plate 1 avoids any interference by the pipe or the flange or flanges being dealt with.

While I have shown a particular form of embodiment of my invention, I am aware that many minor changes therein will readily suggest themselves to others skilled in the art without departing from the spirit and scope of the invention. Having thus described my invention, what I claim as new and desire to protect by Letters Patent is:

1. A wrench for applying and removing threaded flanged couplings to and from threaded pipes, comprising in combination;

a main body plate member adapted to rest flatwise upon and extend beyond the face of a flanged coupling having at least one aperture therethrough,

a pin mounted transversely on one end of the body member, said pin extending outwardly from each side of side body member and adapted for engagement with said flange aperture from either side of the flange,

a handle component integral with the opposite end of said body member,

said body member having means thereon to engage the periphery of the flanged coupling, said means include a pair of elongate right angle sections integral with said body member and located between said pin and said handle component, each of said right angle sections includes two flange portions, one flange portion being perpendicular to the body member and joined thereto along the free edge of said one flange portion, each of said angle sections being located diagonally across the opposite sides of said body member, said engaging means cooperating with said pin in establishing a fulcrum point on the one flange portion by engaging the periphery of said flanged coupling and cooperating to maintain said main body

plate member in flat facial contact with the flanged coupling during either clockwise or counterclockwise operational rotation of the wrench, and said fulcrum point being variable along the length of said one flange portion to engage flanged couplings of various sizes without adjusting said engaging means
